UNITED STATES PATENT OFFICE

2,214,474

REFRIGERATOR

Walter P. Murphy, Chicago, Ill.

Application September 26, 1938, Serial No. 231,645

4 Claims. (Cl. 62—17)

The device relates to refrigerators, cabinets, warehouses, railway cars or other containers for the cooling and/or humidifying of perishable commodities, such as fruits, vegetables, fish or dairy products wherein a liquid refrigerant container is positioned adjacent the ceiling of the refrigerator and a partition is associated with the container so that air cooled by a refrigerant therein is directed and moves downwardly 5 through a flue associated with a vertical wall of the refrigerator and is preferably delivered at the floor of the refrigerator under the foraminous floor rack which supports the lading from the floor of the refrigerator so that the air being 10 warmed by the perishable commodities in the refrigerator rises and returns to adjacent the refrigerant cabinet, and being cooled by the refrigerant, repeats the cycle.

The invention relates to providing a conduit 20 or other means positioned within the vertical wall flue which drains the liquid refrigerant from the container so that while the liquid refrigerant is in the conduit it absorbs heat from the surrounding moving air and thus further cools such 25 air.

A further object is to form the conduit, or provide other means, so that movement of the liquid refrigerant through the conduit is retarded or slowed down so that it will absorb more heat 30 from the surrounding air as the refrigerant passes through the conduit.

Another object is to form and arrange the conduit so as to minimize the crusting of salt on the inside of the conduit. Salt in suspension 35 in water will adhere to some substances and solidify, thereby reducing the size of the conduit.

Another object is to form the conduit of a 40 relatively wide member (horizontally) and of substantially the same depth (horizontally) as the depth of the vertical wall flue and further to form the side walls of such member with vertical corrugations which are positioned so that the downwardly moving air passes through the spaces between the corrugations.

Another object is to provide means so that 45 the liquid refrigerant may be quickly and entirely discharged outside of the cabinet when a dry air is desired inside of the refrigerator and to temporarily or permanently retain all or a 50 part of the liquid refrigerant adjacent the floor of the refrigerator when a damp or wet air is desired inside of the refrigerator.

Another object is to provide means to hold the refrigerant in the container and not let it into 55 the conduit when it is desired to maintain more

refrigerant in the container so as to obtain a lower temperature of air and commodity within the refrigerator. Another object is to have said means operable only from the inside of the refrigerator so that it cannot be accidentally or 5 maliciously operated.

Any liquid refrigerant may be used in my device, such as ice water, brine, dry ice or eutectic ice. The sublimed gas from dry ice is heavier than air and, therefore, falls, and for the purpose 10 of this invention, is a liquid.

The invention specifically relates to railway refrigerator cars wherein liquid refrigerants are desirable because it is not economically practical to provide mechanical refrigeration in such a car. 15

In the drawings:

Fig. 1 is a partial transverse section of a refrigerator car embodying my invention.

Fig. 2 is a side elevation of the pipe and associated pipes shown in Fig. 1.

Fig. 3 shows a modified form of pipe.

Fig. 4 shows a modified form of my invention.

Fig. 5 is a section on line 5—5 of Fig. 4.

The usual parts of a refrigerator car are shown in Fig. 1, such as side sill 2; sub-floor 3; floor 4; 20 floor rack 5 resting upon the floor 4 to provide the space 6; side sheathing 7; side lining 8; false wall 9 which provides the flue 10; side plate 11; roof 12; running board 13; ceiling 14; hatch frame 15 surrounding the hatch 16; refrigerant 25 container 17 and partition 18. The upper portion of the container 17 is preferably provided with apertures 19 through which liquid refrigerant may overflow and flow downwardly through the flue 10.

Air circulates from the lading compartment 25 upwardly through the center duct 26. It is cooled by contact with the refrigerant container 17 and flows downwardly through the flue 10 to the space 6 from which it circulates upwardly to the lading compartment 25. A conduit 27 is provided to drain liquid refrigerant from the container 17 and is positioned within the flue 10 so that the circulating air may contact the conduit 27 and be further cooled. The conduit 40 45 27 may communicate with the container 17 a distance above the bottom thereof, as shown at (28) in Fig. 1 or it may communicate adjacent the bottom of the container. The conduit 27 has a low temperature because it contains refrigerant draining from the container 17.

To increase the surface of the conduit and decrease the rate of flow of the refrigerant through the conduit 27, it may have any one of various forms. Figs. 2 and 3, which are side 50 55

elevations of the conduits, show preferred forms. In Fig. 2, the conduit has several obliquely disposed portions 30 which could be horizontal without departing from the spirit of the invention 5 or the operation thereof. The conduit 27 may also be substantially helical, which form is not shown. In Fig. 3, the conduit 27 is shown formed with a plurality of upwardly inclined portions 31 which are intended to retain at all times some 10 of the refrigerant flowing through the conduit 27. A liquid trap 32 is shown in Fig. 2 to prevent flow of warm air from outside the car into the conduit 27.

A valve 35 is provided in the upper portion of 15 the conduit 27. Said valve may be closed when it is desirable to prevent flow of refrigerant through the conduit 27 so as to retain a larger amount within the container 17. The valve 35 is preferably operable from within the car so as 20 to prevent the accidental or malicious operation thereof.

Means is also provided, preferably a three-way valve 36, for draining the refrigerant from the conduit 27 either to the outside of the car or 25 to the space 6 under the floor rack 5. Some commodities require dry air, so it is often desirable to discharge the liquid outside the car. Other commodities require moist air and liquid under the floor rack 5 would, therefore, be beneficial. 30 As shown in Fig. 3, a valve 37 may be provided to control or prevent flow of liquid from the conduit 27.

In the modification shown in Fig. 4, the conduit comprises a depending part 45 of the refrigerant container 46. As shown in Fig. 5, the 35 part 45 is wide; i. e., its dimension longitudinally of the car is considerable as is shown by its extending substantially between the spaces or posts 47. The part 45 has substantially the same depth 40 as the flue 10, depth being defined as the distance between the side lining 8 and the false wall 9. Some of the walls 48 of the part 45 are formed with vertically disposed corrugations 49. The corrugations stiffen the walls 48 and also 45 provide flues 50 adjacent the side lining 8 and flues 51 adjacent the false wall, the flues 10, 50 and 51 being used for the circulation of cooled air. An auxiliary conduit 52 is provided to drain the container 46 and depending part 45 and a 50 valve 53 is provided at the lower end of the conduit 52. The valve 53 may be closed to prevent escape of refrigerant. Valves 36 and liquid seal 32 may be applied to this modification.

The accompanying drawings illustrate the 55 preferred form of the invention, though it is to be understood that the invention is not limited to the exact details of construction shown and

described, as it is obvious that various modifications thereof, within the scope of the claims, will occur to persons skilled in the art.

I claim:

1. In a refrigerator, the combination of a liquid refrigerant container adjacent the ceiling of the refrigerator, a flue associated with a vertical wall of the refrigerator, a partition associated with said container so that air cooled by a refrigerant in the container moves downwardly through said flue, a foraminous floor rack providing a space below the lading compartment of the refrigerator, a drain conduit for said container which is positioned within said flue so that the refrigerant in said conduit further cools the air moving down said flue, and means whereby the refrigerant in said conduit may be directed to said space below the lading compartment or directed outside of the car. 15

2. In combination with the walls, roof and floor of a refrigerator car, a foraminous rack arranged to support the lading upon said floor and provide a space therebetween, refrigerating equipment below the roof, means associated with one of said walls to conduct liquid from the refrigerating equipment to the lower part of the car, and a valve arranged to conduct said liquid either to the exterior of the car or upon said floor. 20

3. In combination with the walls, roof and floor of a refrigerator car, a foraminous rack arranged to support the lading upon said floor and provide a space therebetween, refrigerating equipment below the roof, means associated with one of said walls to conduct liquid from the refrigerating equipment to the lower part of the car, and an adjustable draining means arranged 25 to conduct said liquid either to the exterior of the car or upon said floor. 30

4. In a refrigerator, the combination of a liquid refrigerant container adjacent the ceiling of the refrigerator, a flue associated with a vertical wall of the refrigerator, a partition associated with said container so that air cooled by a refrigerant in the container moves downwardly through said flue, and a drain conduit from 40 said container which is positioned within said flue so that the refrigerant in said conduit further cools the air moving down said flue, said drain conduit comprising a relatively wide member of substantially the same depth as the depth of said flue and wherein the side walls of said member are formed with vertical corrugations positioned so that the downwardly moving air passes through the spaces between the corrugations. 45

WALTER P. MURPHY.
